(57) CLAIM

The ornamental design for a guitar body, as shown and described.

DESCRIPTION

FIG. 1 is a front perspective view of a guitar body which embodies the design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear perspective view thereof; and,

FIG. 9 is a perspective view of the guitar body in use, showing unclaimed features in dotted lines.

The broken lines in FIGS. 1-9 represent the portions of the design, which form no part of the claim.
